UNITED STATES PATENT OFFICE.

ERICK J. SWEDLUND, OF WILLISTON, NORTH DAKOTA.

SEPARABLE CUFF-BUTTON.

1,353,085.

Specification of Letters Patent. Patented Sept. 14, 1920.

Application filed January 28, 1920. Serial No. 354,649.

To all whom it may concern:

Be it known that I, ERICK J. SWEDLUND, a citizen of the United States, residing at Williston, in the county of Williams and State 5 of North Dakota, have invented certain new and useful Improvements in Separable Cuff-Buttons, of which the following is a specification.

This invention relates to certain new and 10 useful improvements in cuff buttons of the general class known as separable buttons designed more especially for soft shirts, and it has for its objects among others to provide a simple and cheap, yet positive snap fastening embodying a ball joint which permits the button to swing to one side to expose the face of the clamping member and also to allow it to conform to any angle or position that the cuff may assume.

15 It has for a further object to provide a cuff button of this general character composed of few parts, those capable of manufacture at small cost, readily assembled, yet reliable and most efficient in use.

20 Other objects and advantages of the invention will hereinafter appear and the novel features thereof will be particularly pointed out in the appended claims.

The invention is clearly illustrated in the 30 accompanying drawings, which, with the numerals of reference marked thereon, form a part of this specification, and in which

Figure 1 is an elevation showing the cuff button as applied to the cuff.

35 Fig. 2 is an end elevation of the female member.

Fig. 3 is an end elevation of the male member.

Fig. 4 is an elevation with the female 40 member in substantially central section, showing the way in which the two parts of the button are readily separated.

Like numerals of reference indicate like 45 parts throughout the different views.

In carrying out my invention, I form the male member with the face portion 1, the shank 2 and rear portion 3 which terminates in a substantially spherical or ball portion 4 in axial alinement with the shank 2, as seen 50 best in Fig. 4. This may be made of any suitable material, in one or more parts as may be found most expedient.

The female member comprises the face 55 portion 5, the edge of which is curled, as at 6, to embrace the substantially disk portion 7, which latter is at one end of a shank 8,

while the other end of the shank is provided with the member 9 the free edge of which is bent inward forming the angular flange 10, making the space inclosed thereby substantially dovetailed in shape or inwardly tapered, as seen best from Fig. 4.

Within this shank 8 is the tubular member 11, see Fig. 4, the inner end of which is flanged, as at 12, to engage the rounded end 65 of the shank 8 at its junction with the disk portion 7. The said shank is slotted, as at 13, seen clearly in Fig. 2, leaving the resilient portions 14 between such slits, as seen clearly in Fig. 2, and these portions are received within the space inclosed by the tapered flange 10, as seen clearly in Fig. 4. The outer faces of these portions 14 are beveled, as seen at 15, so that when they are 70 in the position seen by full lines in Fig. 4 75 they wedge against the inner wall of the outer portion of the member 10 and form a clutch, as it were, so that the spherical or ball portion 4 of the male member which is received in the central opening 16 between 80 the portions 14, will be firmly grasped, yet allowing of rocking or swivel action or movement of the male member.

In use, the button is applied to the portions 17 and 18 of the cuff in the usual way. 85 Movement of the cuff in any direction will not disconnect the two parts, but when it is desired to separate the parts it is only necessary to press with the thumb or finger 19 against one of the portions 14 when the same 90 will be pressed inward, as indicated by dotted line in Fig. 4, thus relieving its hold on the inner wall of the member 10 and increasing the central opening 16 sufficiently to allow of ready removal of the ball-shaped 95 member 4. The members 14 are sufficiently resilient to normally be forced out in the position in which they are shown by full lines in Fig. 4.

Modifications in detail may be resorted to 100 without departing from the spirit of the invention or sacrificing any of its advantages.

What is claimed as new is:—

1. A separable cuff button comprising a male member and a female member and a 105 ball and socket connection and a bodily slideable clutch lock between the male and female members.

2. A separable cuff button comprising a male member and a female member and a 110 ball and socket connection and a bodily slideable clutch lock between the male and fe-

male members, the socket portion being resilient.

3. A separable cuff button comprising a male member and a female member and a ball and socket connection between the two, the socket portion being wedgingly held in closed position.

4. A separable cuff button comprising a male portion with a spherical terminal and 10 a female portion with a slotted resilient member to frictionally engage said terminal and constituting a wedge lock.

5. A separable cuff button comprising a male portion with a spherical terminal and a

female portion with a slotted resilient member to frictionally engage said terminal, said slotted portion having resilient wedgingly held members.

6. A separable cuff button comprising a male portion with a spherical terminal and 20 a female portion with a slotted resilient member to frictionally engage said terminal, said slotted portion having resilient wedgingly held members, and movable inward to release the wedging engagement to permit 25 of separation of the two portions.

In testimony whereof I affix my signature.
ERICK J. SWEDLUND.
